DESIGN FOR A CARD TABLE

Isaac F. Jewell, Taylorsville, Ky.

Application June 25, 1935, Serial No. 57,397

Term of patent 14 years

To all whom it may concern:

Be it known that I, Isaac F. Jewell, a citizen of the United States, residing at Taylorsville, in the county of Spencer and State of Kentucky, have invented a new, original, and ornamental Design for a Card Table, of which the following is a specification, reference being had to the accompanying drawing, forming part thereof.

Figure 1 is a perspective view of a card table, showing my new design.

Figure 2 is a view in side elevation thereof.

Figure 3 is a top plan view.

I claim:—

The ornamental design for a card table, as shown.

ISAAC F. JEWELL.
